UNITED STATES PATENT OFFICE.

JOSEPH R. MULRONEY, OF FORT DODGE, IOWA, ASSIGNEE TO MULRONEY MANUFACTURING COMPANY, OF FORT DODGE, IOWA, A CORPORATION OF IOWA.

POCKET CONSTRUCTION.

Application filed May 18, 1925. Serial No. 31,136.

To all whom it may concern:

Be it known that I, JOSEPH R. MULRONEY, a citizen of the United States, residing at Fort Dodge, in the county of Webster and 5 State of Iowa, have invented a certain new and useful Pocket Construction, of which the following is a specification.

The object of my invention is to provide a pocket construction which is simple, durable 10 and comparatively inexpensive to manufacture, wherein the pocket affords a means for engaging and retaining a tool or the like therein against accidental displacement.

More particularly, my invention relates to 15 a pocket construction wherein an elastic member is used on the back piece of the pocket, which elastic member is so arranged and secured to the front piece of the pocket or the garment itself as to form a receiver 20 for a tool or the like, and holding it in position when such tool is inserted between the elastic member and the front piece of the pocket.

Still a further object is to provide an 25 elastic member in the back piece of the pocket, which is free to expand a maximum amount for making it easy to insert an article between itself and the front piece 30 of the pocket, and when such article is inserted therebetween, to retain such article in place.

Still a further object is to arrange the 35 elastic member in the back piece of the pocket so that it will not be noticeable to anyone, the front piece of the pocket serving as a means to conceal the elastic member from view.

Still a further object is to form an opening in the garment itself, which opening is 40 covered from view by the front piece of the pocket and the securing of an elastic member to the garment itself covering the opening formed in the garment.

Reference is here made to my copending 45 application for a pocket construction, filed May 18, 1925, Serial No. 31,135.

With these and other objects in view, my invention consists in the construction, arrangement and combination of the various 50 parts of my device, whereby the objects contemplated are attained, as hereinafter more fully set forth, pointed out in my claim, and illustrated in the accompanying drawings, in which:

Figure 1 is a front, plan view of a portion

of a garment with my improved pocket construction shown thereon, parts being broken away of the front piece to better illustrate the arrangement of the back piece.

Figure 2 is a central, vertical, sectional view taken on the line 2—2 of Figure 1.

Figure 3 is a horizontal, sectional view taken on the line 3—3 of Figure 1.

Figure 4 is a view similar to Figure 1 showing an opening in the garment of substantially the same size as the pocket itself.

Figure 5 is a front view of a pocket construction wherein the back piece, is formed independent of the garment itself and stitched thereto, the back piece including an elastic member; and

Figure 6 is a central, sectional view taken on line 6—6 of Figure 5.

In the accompanying drawings, I have used the reference numeral 10 to indicate generally a garment, preferably of the work type, sometimes called an overall.

The pocket construction may be placed on the garment at any suitable point, and in the drawings, I have shown the pocket adjacent the seam 11 of the garment.

My pocket construction comprises a front piece 12, which is secured along one marginal edge by the stitches 13, which also serve to retain the seam 11.

The bottom of the front piece 12 and the free side is secured to the garment 10 by means of the stitches 14.

The upper edge of the front piece 12 is turned over so as to form a binder 15, which 90 is fastened to the body portion of the front piece by the stitches 16.

The upper edge of the front piece 12 is open so that the front piece and the garment 95 itself form the pocket.

In order to hold a pair of pliers, or any other such article, in position within the pocket, I form an opening 17 in the garment 10, which opening is of less size than the front piece 12.

An elastic member 18 is stitched or otherwise fastened to the garment 10 along the edges of the material formed by the opening 17.

In the drawings, I have shown stitches 19 105 for fastening the elastic member to the garment 10, although any suitable fastenings may be used.

It will be here seen that the elastic member 18 takes the place of the cloth or fabric 110

which was removed by the forming of the opening 17.

The elastic member 18 is secured at two spaced points to the front piece 12 by 5 stitches or fastenings of any suitable kind 20 for dividing the pocket into sections.

The fastenings 20 terminate short of the top and bottom edges of the elastic member 18 so that the elastic member 18 is free to 10 expand easier than it would if the stitches 20 extended to the top and bottom edges of the elastic member.

If the stitches 20 extended to the top and 15 bottom edges of the elastic member, then 13 there would practically be a fixed relationship between the cloth of the garment 10 adjacent the stitches 19, and the front piece 12, whereas in the present case, the front piece 12 is free to move forwardly owing to 20 the fact that it is only connected to the elastic member between its side edges.

In Figure 4 of the drawings, I have shown 25 the opening 17 of the greater size than the opening in Figure 1 of the drawings, although the principle and function of the elastic member 18 in the case of Figure 4 is 20 the same in every respect as the elastic member shown in Figure 1.

In Figure 5 of the drawings, I have shown 30 the back piece of the pocket made independent of the garment, and I have referred to the back piece by the reference numeral 21.

The back piece in this case includes a pair 35 of small pieces 21^a and 21^b, which are connected together by an elastic member 22, which serves the same purpose as the elastic member 18.

The pieces 21^a, 21^b and 22 are all fastened 40 to the garment 10.

The back piece 21 is secured to the garment 10 by the stitches 23, which run along the two side edges, bottom and top of the back piece 21.

The garment 10 is formed with a slot or 45 slit opening 24, which is slightly below the upper edge of the back piece 21 and through the slot 24 access is had into the pocket formed by the garment 10, and the back piece 21.

The edges of the slot or slit opening 24 may be bent over so as to form a double edge, as at 25.

The elastic member 22, as shown in Figure 5 of the drawing, is secured to the garment 10, which serves as the front piece of the pocket, by stitches or fastenings 20 similar to those described in reference to Figures 1 and 4.

It will be noted that there is no cloth 60 covering over the elastic which would interfere with the free elasticity of the elastic member.

It will be particularly noted that the elastic member which I employ may be 65 easily and quickly fastened to the back piece of the pocket by simply forming an opening in the garment, and covering it with the elastic member or in the case of Figure 5, fastening two small pieces of cloth to the 70 top and bottom edges of the elastic, all of which can be done at a comparatively small cost.

Some changes may be made in the construction and arrangement of the various 75 parts of my invention, without departing from the real spirit and purpose of my invention, and it is my intention to cover by claim, any modified forms of structure or use of mechanical equivalents, which may so be reasonably included within its scope.

I claim as my invention:

A pocket construction for garments and the like comprising a front and back piece of textile material stitched together along 85 two sides and the bottom edge, said back piece having an opening therein of less size than the front piece, an elastic member inserted in said opening and fastened to the material adjacent the edges of the opening, 90 said elastic member being completely hidden from view by the front piece and fastenings between said elastic member and the front piece, said fastenings terminating short of the top of the elastic member for permitting 95 unrestricted elasticity of the upper portion of the elastic member above the fastenings.

Des Moines, Iowa, May 14, 1925.

JOSEPH R. MULRONEY.
